MULTIPLEX TRANSMISSION SYSTEM FOR TELEVISION SIGNALS

Louis Le Blan, Paris, France, assignor, by mesne assignments, to North American Philips Company, Inc., New York, N.Y., a corporation of Delaware

Filed May 9, 1955, Ser. No. 507,653

Claims priority, application France May 10, 1954

10 Claims. (Cl. 178—6)

This invention relates to multiplex transmission systems for signals relating to television pictures or similar pictures scanned in lines in which at the transmitting end each of two signals is dotted with the aid of an associated dotting signal, whereafter the signals thus dotted are combined and the combined signal is supplied to a common transmission path, and in which at the receiving end the transmitted signal is dotted with the aid of each of two dotting signals, which as far as possible are in the same phase relationship with respect to the transmitted signal as are the dotting signals at the transmitting end.

It is to be noted that the term "dotting" is to be understood to mean modulating a signal on a series of pulses having the particularity that the phase thereof during one frame-changing period is shifted by π -radians with respect to the phase of the same series of pulses during a subsequent frame-changing period. As is well-known, this may be achieved inter alia by choosing the pulse repetition frequency to be equal to an odd multiple of half the line frequency used in the system.

It is also to be noted that a reference signal must be present in the transmitted signal to ensure that the dotting signals at the receiving end are in the same phase relationship with the transmitted signal as are the dotting signals at the transmitting end. Said reference signal may be provided, for example, in the form of a sinusoidal oscillation having a frequency equal to the pulse repetition frequency of the dotting signals and occurring during the back porches of the line synchronizing pulses.

In known systems the two dotting signals are also relatively shifted by π -radians both at the transmitting and the receiving ends.

Such systems afford the advantage that two signals, for example relating to television pictures, are transmitted in a frequency band having a width not larger than that of the frequency band necessary for the ordinary transmission of one of said signals.

This is offset by the fact that interference in the reproduced pictures occurs during the reproduction of the signals thus transmitted. However, due to the said phase relation during subsequent frame-changing periods, said interference is such that an interference which occurs during one frame-changing period is compensated at least visually by an analogous interference which occurs during the subsequent frame-changing period. Strictly speaking, this is true only if the signal leading to the interference does not vary from picture to picture. It is known that, if the variations are not excessive, this also approximately holds good for signals having different forms during subsequent frame-changing periods.

However, if a small deviation occurs in the phase relationship (hence in the synchronisation) between the series of pulses at the transmitting end and the series of pulses at the receiving end, crosstalk of one signal in the other is involved, so that during reproduction the image of one signal also shows an image of the other signal.

The object of the invention is to suppress considerably the troublesome influence of deviations in the said synchronisation. For this purpose the system according to

2

the invention is characterized in that, at the transmitting end, the bandwidth of one dotted signal is limited to a frequency range comprised between 0 and a frequency equal to half the pulse repetition frequency of the dotting signals and that the other dotted signal is limited to a frequency range comprised between a frequency equal to half the pulse repetition frequency of the dotting signals and a frequency equal to the said pulse repetition frequency, the two signals thus limited in bandwidth being combined, and that at the receiving end the combined signal transmitted is divided into two parts, of which one has a bandwidth comprised between 0 and a frequency equal to half the pulse repetition frequency of the dotting signals and the other has a bandwidth comprised between a frequency equal to half the pulse repetition frequency of the dotting signals and a frequency equal to the said pulse repetition frequency, each part being dotted with the aid of a dotting signal having a phase relationship with the associated part equal to that of the dotting signal used at the transmitting end for obtaining the corresponding part.

In order that the invention may be readily carried into effect, it will now be described, by way of example, with reference to the accompanying drawing, in which

25 Fig. 1 shows a transmission characteristic that may be used with the invention.

Fig. 2 shows diagrammatically an embodiment of a transmitter according to the invention and

30 Fig. 3 shows diagrammatically an embodiment of a receiver according to the invention.

The signals to be transmitted, relating to television pictures of similar pictures scanned in lines, are indicated hereinafter by f_1 and f_2 . The bandwidth of these signals is assumed to be comprised between the frequencies 0 and N_0 .

35 According to the known method, the signals f_1 and f_2 may be transmitted in a frequency range which is not larger than that required for the ordinary transmission of one of said signals.

40 For this purpose the signal f_1 , for example, is dotted with the aid of a signal g_1' :

$$g_1' = A \left\{ 1 + \sum_{n=1}^{\infty} 2 \cos n\omega_0 t \right\}$$

45 wherein A indicates a constant and $\omega_0 = 2\pi N_0$. As is well known, it suffices to utilise a signal g_1 :

$$g_1 = A \{ 1 \pm 2 \cos \omega_0 t \}$$

50 in view of the fact that the higher harmonics of g_1 , on account of the limited bandwidth of the transmission path, are immaterial in the transmission. It will also be seen that in g_1 , instead of $+2 \cos \omega_0 t$, there is written: $\pm 2 \cos \omega_0 t$. This indicates that during one frame-changing period g_1 has the form $A \{ 1 + 2 \cos \omega_0 t \}$ and during

55 the subsequent period g_1 has the form $A \{ 1 - 2 \cos \omega_0 t \}$, so that each time $t=0$ at the beginning of a new frame-changing period, thus expressing the phase difference of π -radians prevailing between the series of pulses during one frame-changing period and the series of pulses during a subsequent frame-changing period.

60 Assuming the signal f_1 to have the form:

$$f_1 = a \cos \omega_1 t + b \cos \omega_2 t$$

wherein

$$\omega_1 < \omega_0 \text{ and } \omega_2 < \omega_0$$

65 dotting then provides a signal $f_1 \cdot g_1$ which is supplied to a low-pass filter having a cut-off frequency N_0 . The output signal of this filter, indicated diagrammatically by $[f_1 \cdot g_1]_{0, \omega_0}$, may be written as follows:

$$70 [f_1 \cdot g_1]_{0, \omega_0} = A [a \cos \omega_1 t + b \cos \omega_2 t \pm a \cos (\omega_0 - \omega_1) t \pm b \cos (\omega_0 - \omega_2) t]$$

The signal f_2 is dotted in an analogous manner with the aid of a signal g_2 :

$$g_2 = A\{1 \mp 2 \cos \omega_0 t\}$$

the signal f_2, g_2 thus dotted also being supplied to a low-pass filter having a cut-off frequency N_0 . The output signal of this filter: $[f_2, g_2]0, \omega_0$, iff f_2 has the form:

$$f_2 = c \cos \omega_3 t + d \cos \omega_4 t$$

wherein

$$\omega_3 < \omega_0 \text{ and } \omega_4 < \omega_0$$

is

$$[f_2, g_2]0, \omega_0 = A[c \cos \omega_3 t + d \cos \omega_4 t \mp c \cos(\omega_0 - \omega_3)t \mp d \cos(\omega_0 - \omega_4)t]$$

$[f_1, g_1]0, \omega_0$ and $[f_2, g_2]0, \omega_0$ are now combined and the signal thus formed $[f_1, g_1]0, \omega_0 + [f_2, g_2]0, \omega_0$ is supplied to the transmission path, which may be a cable, but naturally also the air. In the latter case, the combined signal is modulated on a high-frequency carrier wave, the modulated carrier wave being supplied to a transmitting aerial.

At the receiving end there is thus produced, if desired with the use of an intermediate-frequency stage and a video-detector, the signal $[f_1, g_1]0, \omega_0 + [f_2, g_2]0, \omega_0$.

Said signal is dotted, on the one hand, by a signal G_1 :

$$G_1 = B[1 \pm 2 \cos \omega_0 t]$$

and, on the other, by a signal G_2 :

$$G_2 = B[1 \mp 2 \cos \omega_0 t]$$

It is to be noted that the signals G_1 and G_2 are substantially identical with the signals g_1 and g_2 that are used at the transmitting end. In order to ensure this equality, it is possible in known manner to add to the signal to be transmitted a reference signal with which, or from which, the signals G_1 and G_2 may be obtained.

However, interference in the transmission path, or in the receiver, may temporarily neutralize the equality, so that at the receiving end, instead of signals G_1 and G_2 , the signals G'_1 and G'_2 are produced:

$$G'_1 = D[1 \pm 2 \cos(\omega_0 t + \delta)]$$

$$G'_2 = B[1 \mp 2 \cos(\omega_0 t + \delta)]$$

wherein δ indicates a phase deviation.

Dotting of the signal $[f_1, g_1]0, \omega_0 + [f_2, g_2]0, \omega_0$ with the aid of G'_1 provides, after limitation of bandwidth to N_0 , a signal f'_1 :

$$f'_1 = A \cdot B \cdot [a \cos \omega_1 t + b \cos \omega_2 t \pm a \cos(\omega_0 - \omega_1)t \pm b \cos(\omega_0 - \omega_2)t + c \cos(\omega_0 - \omega_3)t \mp d \cos(\omega_0 - \omega_4)t \pm a \cos\{(\omega_0 - \omega_1)t + \delta\} \pm b \cos\{(\omega_0 - \omega_2)t + \delta\} \pm a \cos\{(\omega_0 - \omega_3)t + \delta\} \pm d \cos\{(\omega_0 - \omega_4)t + \delta\} - c \cos(\omega_3 t + \delta) - d \cos(\omega_4 t + \delta)]$$

If, now, $\delta = 0$, and hence $G'_1 = G_1$, then f'_1 changes to f'_1 :

$$f'_1 = A \cdot B \cdot [a \cos \omega_1 t + b \cos \omega_2 t \pm a \cos(\omega_0 - \omega_1)t \pm b \cos(\omega_0 - \omega_2)t]$$

Considering that each of the terms $\pm a \cos(\omega_0 - \omega_1)t$ and $\pm b \cos(\omega_0 - \omega_2)t$ is, on the average, equal to zero during two frame-changing periods and that these terms in themselves produce only a point structure in the image, it will be evident that the eye is substantially not affected as a result thereof.

However, if $\delta \neq 0$, it appears from the above-mentioned expression for f'_1 that it also contains, although to a small extent, the signal f_2 , which naturally is troublesome.

According to the invention, however, at the transmitting end, the bandwidth of the signal f_1, g_1 is limited to a frequency range comprised between 0 and $\frac{1}{2}N_0$. Assuming that there also applies:

$$0 < \omega_1 < \frac{1}{2}\omega_0 \text{ and } \frac{1}{2}\omega_0 < \omega_2 < \omega_0$$

the output signal $[f_1, g_1]0, \frac{1}{2}\omega_0$ of the filter bringing about the limitation in bandwidth thus is:

$$[f_1, g_1]0, \frac{1}{2}\omega_0 = A[a \cos \omega_1 t \pm b \cos(\omega_0 - \omega_1)t]$$

According to the invention, the bandwidth of the signal f_2, g_2 is limited to a frequency range comprised between $\frac{1}{2}N_0$ and N_0 .

Assuming that the following relationships apply:

$$0 < \omega_3 < \frac{1}{2}\omega_0 \text{ and } \frac{1}{2}\omega_0 < \omega_4 < \omega_0$$

then the out-signal $[f_2, g_2]0, \frac{1}{2}\omega_0, \omega_0$ of the filter bringing about the limitation in bandwidth is:

$$[f_2, g_2]0, \frac{1}{2}\omega_0, \omega_0 = A[\mp c \cos(\omega_0 - \omega_3)t \pm d \cos \omega_4 t]$$

The signals $[f_1, g_1]0, \frac{1}{2}\omega_0$ and $[f_2, g_2]0, \frac{1}{2}\omega_0, \omega_0$ are combined again, the resultant signal

$$[f_1, g_1]0, \frac{1}{2}\omega_0 + [f_2, g_2]0, \frac{1}{2}\omega_0, \omega_0$$

being supplied to the transmission path.

At the receiving end there is obtained again, if desired with the use of an intermediate-frequency stage and a video-detector, the signal $[f_1, g_1]0, \frac{1}{2}\omega_0 + [f_2, g_2]0, \frac{1}{2}\omega_0, \omega_0$.

The signal is supplied, on the one hand, to a low-pass filter having a cut-off frequency $\frac{1}{2}N_0$, and, on the other, to a band-pass filter having a transmission range comprised between $\frac{1}{2}N_0$ and N_0 . Consequently, signals $[f_1, g_1]0, \frac{1}{2}\omega_0$ and $[f_2, g_2]0, \frac{1}{2}\omega_0, \omega_0$ are set up at the output of the low-pass filter and at the output of the band-pass filter respectively.

The signal $[f_1, g_1]0, \frac{1}{2}\omega_0$ is dotted with the aid of a signal G_1 :

$$G_1 = B[1 \pm 2 \cos \omega_0 t]$$

and the signal $[f_2, g_2]0, \frac{1}{2}\omega_0, \omega_0$ is dotted with the aid of a signal G_2 :

$$G_2 = B[1 \mp 2 \cos \omega_0 t]$$

In this case also interference in the synchronisation between g_1 , G_1 and g_2 , G_2 may arise, so that at the receiving end signals G'_1 and G'_2 are produced:

$$G'_1 = B[1 \pm 2 \cos(\omega_0 t + \delta)]$$

$$G'_2 = B[1 \mp 2 \cos(\omega_0 t + \delta)]$$

wherein δ , as before, indicates the undesired deviation.

Dotting of $[f_1, g_1]0, \frac{1}{2}\omega_0$ by G'_1 provides a signal F'_1 :

$$F'_1 = AB[a \cos \omega_1 t \pm \delta \cos(\omega_0 - \omega_2)t \pm a \cos\{(\omega_0 - \omega_1)t + \delta\} \pm a \cos\{(\omega_0 - \omega_2)t + \delta\} \pm b \cos\{(\omega_0 - \omega_3)t + \delta\} \pm b \cos\{(\omega_0 - \omega_4)t + \delta\} \pm b \cos\{(\omega_0 - \omega_3)t + \delta\} \pm b \cos\{(\omega_0 - \omega_4)t + \delta\}]$$

Limitation of bandwidth to N_0 provides a signal F'_1 :

$$F'_1 = AB[a \cos \omega_1 t \pm b \cos(\omega_0 - \omega_2)t \pm a \cos\{(\omega_0 - \omega_2)t + \delta\} \pm b \cos\{(\omega_0 - \omega_3)t + \delta\}]$$

It is observed that limitation of bandwidth is not absolutely necessary, since the term $\pm a \cos\{(\omega_0 + \omega_1)t + \delta\}$ has a compensating effect for the eye in subsequent frame-changing periods and the term $b \cos\{(\omega_0 - \omega_2)t + \delta\}$ has a high frequency such as to provide only a fine point structure, at least if this high frequency is reproduced by the picture tube.

The terms $\pm b \cos(\omega_0 - \omega_2)t$ and

$$\pm a \cos\{(\omega_0 - \omega_1)t + \delta\}$$

also visually have a compensating effect in subsequent frame-changing periods; the terms playing a part in the structure of the image thus are: $a \cos \omega_1 t + b \cos(\omega_0 - \omega_2)t + \delta$. If $\delta = 0$, this signal thus is exactly identical, except for a proportionality constant, with the signal f_1 , produced at the transmitting end. However, if $\delta \neq 0$, this signal is no longer exactly identical with f_1 , but interference resulting from the signal f_2 is not present therein. It is observed that the wrong phase in $b \cos(\omega_0 - \omega_2)t + \delta$ leads for $\delta \neq 0$ to a certain lack of definition in the image reproduced. The experience with ordinary black-and-white television receivers having a phase characteristic which

is usually not exactly linear, leading to analogous phase

deviations, shows that such lack of definition is usually substantially imperceptible.

Dotting of the signal $[f_2g_2] \frac{1}{2}\omega_0, \omega_0$ with the aid of a dotting signal G_2' provides, after limitation in bandwidth to N_0 , a signal F_2' :

$$F_2' = AB[c \cos(\omega_3 t + \delta) + d \cos(\omega_4 t \mp c \cos(\omega_0 - \omega_3)t + \delta)]$$

The terms $\mp c \cos(\omega_0 - \omega_3)t$ and $\mp d \cos(\omega_0 - \omega_4)t + \delta$ as before, visually have a compensating effect in subsequent frame-changing periods and the terms playing a part in the structure of the image thus are

$$c \cos(\omega_3 t + \delta) + d \cos \omega_4 t$$

For $\delta = 0$ this signal is again exactly identical with the initial signal f_2 ; for $\delta \neq 0$ there is again introduced a certain phase deviation leading to lack of deviation, but even for $\delta \neq 0$ crosstalk of the signal f_1 in the signal f_2 does not occur.

It will be evident from the foregoing that a certain phase relation between the series of pulses g_1, g_2 and g_1, G_2 and G_1', G_2' , as required in the known system (hence that, for example, the signals g_1 and g_2 are relatively shifted by π -radians), is not required at all in the system according to the invention. This implies that the same series of pulses may be used for g_1 and g_2 and hence also for G_1 and G_2 .

Fig. 2 shows diagrammatically one embodiment of a transmitter according to the invention, in which reference numeral 3 indicates a lowpass filter having a cut-off frequency N_0 . Said filter has supplied to it one of the signals to be transmitted (in the figure the signal f_1) relating to, for example, a television picture. 6 also indicates a lowpass filter having a cut-off frequency N_0 and which has the other signal f_2 supplied to it. The output signals of the lowpass filters 3 and 6 are supplied to samplers or gates 2 and 5. 1 indicates an oscillator producing a series of pulses have a pulse repetition frequency N_0 . Said series of pulses may have the form

$$A \left[1 + \sum_{n=1}^{\infty} 2 \cos n\omega_0 t \right]$$

but, as mentioned hereinbefore, it also suffices to utilize a signal $A[1 \pm 2 \cos \omega_0 t]$. The sign $\pm$ indicates that the phase of the signal produced by the oscillator 1 during one frame-changing period is shifted by π -radians, with respect to the signal during a subsequent period. The output signal of the oscillator 1, for example g_1 , is supplied to the sampler 2, in which the signal f_1g_1 is thus produced. The output signal of the oscillator 1 is also supplied to a device 4, in which it is delayed by π -radians, the output signal of the device 4, hence g_2 , being supplied to the sampler 5 in which the signal f_2g_2 is thus produced. The output signal of sampler 2 is supplied to a lowpass filter having a cut-off frequency $\frac{1}{2}N_0$ and the output signal of sampler 5 is supplied to a bandpass filter 8 having a transmission range between the frequencies $\frac{1}{2}N_0$ and N_0 . The output signals of the filters 7 and 8 are combined in an adder 9, the output signal of which is supplied to a modulator 10 in which it is modulated on a high-frequency carrier wave supplied by the source 10', which modulated carrier wave is supplied to a transmitting aerial.

Fig. 3 shows diagrammatically one embodiment of a receiver according to the invention. The signal transmitted by a transmitter as shown in Fig. 2 is received by a receiving aerial 11 and supplied to a device 12 comprising the high-frequency and intermediate-frequency stages. The output signal of device 12 is supplied to a video-detector 13, producing the signal

$$[f_1g_2]0, \frac{1}{2}\omega_0 + [f_2g_2] \frac{1}{2}\omega_0, \omega_0$$

This signal is supplied, on the one hand, to a low-pass filter 21 having a cut-off frequency $\frac{1}{2}N_0$ and, on the other, to a band-pass filter 22 having a transmission range

comprised between the frequencies $\frac{1}{2}N_0$ and N_0 . The output signal of the low-pass filter 21 is supplied to a sampler 19 and the output signal of bandpass filter 22 is supplied to a sampler 20. The series of pulses present in the output signal of video-detector 13 in this case serves itself as the reference signal required for producing the dotting signals. For this purpose the output signal of detector 13 is also supplied to a bandpass filter 14 having a very narrow transmission range located in the vicinity of the frequency N_0 ; the output signal of said filter is limited on two sides in a device 15. The signal thus limited is supplied to a lowpass filter 16 having a cut-off frequency comprised between N_0 and $2N_0$. This results in a substantially sinusoidal voltage at the output of said filter having a frequency equal to N_0 . With the aid of the output signal of the filter 16, signals G_1 and G_2 are produced in devices 17 and 18, respectively, the signals G_1 and G_2 being supplied to samplers 19 and 20. The output signals of the samplers 19 and 20 are supplied to lowpass filters 23 and 24, respectively, both of which have a cut-off frequency N_0 . Their output signals may further be supplied to picture tubes (not shown).

As mentioned before, a certain phase relation between the signals g_1 and g_2 and a corresponding phase relation between the signals G_1 and G_2 is not required. However, this is true only if the filters 7 and 21 have a sharp cut-off action at the frequency $\frac{1}{2}N_0$ and, similarly, the filters 8 and 22 have a sharp cut-off action at the frequency $\frac{1}{2}N_0$. However, filters having very sharp cut-off actions can be manufactured with difficulty only and the frequency ranges of the signals $[f_1g_1]0, \frac{1}{2}\omega_0$ and $[f_2g_2] \frac{1}{2}\omega_0, \omega_0$ both at the transmitting end and at the receiving end usually overlap a little in the vicinity of the frequency $\frac{1}{2}N_0$. In view thereof it is still, preferable to bring about a phase difference of π -radians between g_1 and g_2 and a similar phase difference between the signals G_1 and G_2 . Furthermore, in this case it is preferable for the total transmission characteristic of the signal $[f_1g_1]0, \frac{1}{2}\omega_0$ to be so chosen that the signal for the frequency $\frac{1}{2}N_0$ is attenuated twice as much as the lower frequencies of this signal and also preferable for the transmission characteristic of the signal $[f_2g_2] \frac{1}{2}\omega_0, \omega_0$ to be so chosen that the signal for the frequency $\frac{1}{2}N_0$ is attenuated twice as much as the higher frequencies of this signal. Fig. 1 shows the transmission characteristics for the said two signals in which the transmissivity Γ is plotted as a function of the angular frequency ω . The curve A, B, C, D shows the transmission characteristic for the signal $[f_1g_1]0, \frac{1}{2}\omega_0$ and the curve E, C, F, G, H, I shows the transmission characteristic for the signal $[f_2g_2] \frac{1}{2}\omega_0, \omega_0$. The figure shows that in both transmission characteristics the transmissivity is reduced by half at the frequency $\frac{1}{2}N_0$. It also appears from simple calculation that, in order to avoid crosstalk between the signals f_1 and f_2 in the frequency range comprised between the frequencies E and D, at least in the case of complete synchronisation between the signals g_1, G_1 and g_2, G_2 , it is preferable to provide for the slope of the transmission characteristic for the signal $[f_1g_1]0, \frac{1}{2}\omega_0$ between the frequencies E and D to be equal to that of the transmission characteristic for the signal $[f_2g_2] \frac{1}{2}\omega_0, \omega_0$ between the frequencies E and D.

What is claimed is:

1. A multiplex transmission system for television signals, comprising transmitter means for producing two video signals, means for producing a first dotting signal having a constant repetition frequency, sampler means for dotting said video signals with said dotting signal, means for limiting the bandwidth of one of said dotted signals to a first frequency range lying substantially between zero and one-half of said repetition frequency, means for limiting the bandwidth of the other of said dotted signals to a second frequency range lying substantially between one-half of said repetition frequency and said repetition frequency, means for combining the dotted signals thus limited in bandwidth, and receiver means for

receiving the combined signals and comprising means for separating said combined signals into a first signal portion having a bandwidth lying substantially between the frequencies of zero and one-half of said repetition frequency and a second signal portion having a bandwidth lying substantially between the frequencies of one-half of said repetition frequency and said repetition frequency, means for producing a second dotting signal corresponding to said first dotting signal, sampler means for dotting said first signal portion with said second dotting signal in phase with the transmitted dotted signal lying in said first frequency range, and sampler means for dotting said second signal portion with said second dotting signal in phase with the transmitted dotted signal lying in said second frequency range.

2. A system as claimed in claim 1, in which said means for limiting the bandwidth of one of said dotted signals to a first frequency range comprises a filter having a transmission characteristic curve which has a generally flat amplitude level which decreases in the vicinity of one-half of said repetition frequency and has an amplitude equal to one-half of said amplitude level at said frequency of one-half of said repetition frequency, and in which said means for limiting the bandwidth of the other of said dotted signals to a second frequency range comprises a filter having a transmission characteristic curve which has a generally flat amplitude level which decreases in the vicinity of said frequency of one-half of said repetition frequency and has an amplitude equal to one-half of said last-named amplitude level at said frequency of one-half of said repetition frequency.

3. A system as claimed in claim 2, in which said filters are constructed to provide equal rates of slope of their respective characteristic curves in the vicinity of said frequency of one-half the repetition frequency, whereby said decreasing amplitudes of the transmission characteristic curves are complementary about said frequency of one-half of said repetition frequency.

4. A system as claimed in claim 1, in which said transmitter sampler means for dotting the video signals includes phasing means connected so that said video signals are dotted π radians out-of-phase.

5. A transmitter for use in a multiplex transmission system for television video signals, comprising means for producing a first dotting signal having a constant repetition frequency, sampler means for dotting said video signals with said dotting signal, means for limiting the bandwidth of one of said dotted signals to a first frequency range lying substantially between zero and one-half of said repetition frequency, means for limiting the bandwidth of the other of said dotted signals to a second frequency range lying substantially between one-half of said repetition frequency and said repetition frequency, and means for combining the dotted signals thus limited in bandwidth.

6. A transmitter as claimed in claim 5, in which said

sampler means for dotting the video signals includes phasing means connected so that said video signals are dotted π radians out-of-phase.

7. A receiver for receiving a combined television signal composed of a first dotted video signal having a frequency bandwidth lying substantially between zero and one-half of the dotting repetition frequency and a second dotted video signal having a frequency bandwidth lying substantially between one-half of said dotting repetition frequency and said dotting repetition frequency, said receiver comprising means for separating said combined signals into a first signal portion having a bandwidth lying substantially between the frequencies of zero and one-half of said repetition frequency and a second signal portion having a bandwidth lying substantially between the frequencies of one-half of said repetition frequency and said repetition frequency, means for producing a dotting signal corresponding to the dotting of said video signals, sampler means for dotting said first signal portion with said dotting signal in phase with the transmitted dotted signal lying in said first frequency range, and sampler means for dotting said second signal portion with said dotting signal in phase with the transmitted dotted signal lying in said second frequency range.

8. A receiver as claimed in claim 7, in which said means for separating the combined signals comprises a pair of filters having frequency transmission characteristics which have generally flat amplitude levels and which decrease in amplitude in the vicinity of a frequency equal to one-half of said dotting repetition frequency and have amplitudes equal to one-half of said amplitude levels at said frequency of one-half of said repetition frequency.

9. A receiver as claimed in claim 8, in which filters are constructed to provide equal rates of slope of their respective characteristic curves in the vicinity of said frequency of one-half the repetition frequency, whereby said decreasing amplitudes of the transmission characteristics are complementary about said frequency of one-half of said repetition frequency.

10. A receiver as claimed in claim 8, in which said video signals are dotted π radians out-of-phase, and in which said sampler means include phasing means connected so that said signal portions are dotted π radians out-of-phase.
